[57] CLAIM

The ornamental design for a reclosable package, shown and described.

DESCRIPTION

FIG. 1 is a front perspective view of a reclosable package showing my new design;

FIG. 2 is a sectional elevation taken along line 2—2 of FIG. 1;

FIG. 3 is a top plan view thereof;

FIG. 4 is a front elevation thereof;

FIG. 5 is a bottom plan view thereof;

FIG. 6 is a left side elevation thereof;

FIG. 7 is a right side elevation thereof;

FIG. 8 is a rear side view thereof;

FIG. 9 is a front perspective view thereof similar to FIG. 1; with graphics card; and

FIG. 10 is a rear side elevation thereof; similar to FIG. 8; with graphics card.

The broken lines showing of graphics card in FIGS. 9 and 10 are shown for illustrative purpose only and forms no part of the claim.
